C. W. ARMBRUST.

BRAKE SHOE.

APPLICATION FILED FEB. 19, 1916.

1,210,384.

Patented Dec. 26, 1916.

UNITED STATES PATENT OFFICE.

CHARLES W. ARMBRUST, OF CHICAGO, ILLINOIS, ASSIGNEE, BY MESNE ASSIGNMENTS,
TO THE AMERICAN BRAKE SHOE & FOUNDRY COMPANY, OF WILMINGTON, DELA-
WARE, A CORPORATION OF DELAWARE.

BRAKE-SHOE.

1,210,384.

Specification of Letters Patent. Patented Dec. 26, 1916.

Application filed February 19, 1916. Serial No. 79,237.

To all whom it may concern:

Be it known that I, CHARLES W. ARMBRUST, a citizen of the United States, residing at Chicago, in the county of Cook and State of Illinois, have invented a certain new and useful Improvement in Brake-Shoes, of which the following is a full, clear, concise, and exact description, reference being had to the accompanying drawings, 10 forming a part of this specification.

My invention relates to brake shoes and has for its object the provision of an improved back for brake shoes which shall be simple in construction and easy of manufacture.

My invention contemplates broadly the provision of a blank in such a way that a key lug may be formed from this blank without distorting the remaining portions 20 of the blank, by which I mean the remaining portions of the blank are to be left substantially in the shape of an arc, circle or curve. The finger which forms the lug may be either in one piece, or may consist of a 25 pair of fingers which coöperate to form the key lug.

I will explain several forms of carrying out my invention more in detail by referring to the accompanying drawing, in 30 which:

Figure 1 is a longitudinal sectional view of a brake shoe having my improved back in position; Fig. 2 is a sectional view on line *b*—*b* of Fig. 1; Fig. 3 is a top view of 35 the back before uniting with the shoe; Fig. 4 is a top view of a blank showing a modified form, and Fig. 5 is a top view of a blank showing another modified form.

Referring more particularly to Fig. 1, 40 my improved back 1 is shown as mounted in place within a shoe 2. The back 1 preferably is made from a blank shown more clearly in Fig. 3.

In Figs. 1, 2 and 3, I show my improved 45 back 1 in which the key lug 5 is formed of two fingers 10 and 11, which fingers are drawn out from the body portion 3 to form opposite sides of the key lug 5. The fingers are bent upwardly substantially into L- 50 shape and approach each other from opposite sides, overlapping slightly at the central top portion, as more clearly apparent from Fig. 3. A key slot 6 is of course provided

as readily understood. Openings 12 are left in the edges of the fingers to permit the 55 metal of the shoe 2 to pass therethrough and more thoroughly interlock and hold them in the proper position. It will be seen from this that the metal for the key lug is formed from the body of the back without 60 in any way distorting this back except to give it the necessary curvature. Holes 13 are provided in the body portion 3 to more thoroughly unite the back and the shoe.

In Fig. 4, I show a modified form along 65 the same general lines as shown in Figs. 1 and 3, which modified form is shown merely in the shape of a blank, this blank having the body portion 3 provided with holes 14 which perform the same function as the 70 holes 13 in Fig. 3. The key lug is then formed from the two fingers 15, and 15, which fingers are bent upwardly along the lines 16, 16, suitable holes 17 being provided more thoroughly to have the parts 75 united together. The fingers 15 also have cut-away portions 18, which cut-away portions, when these fingers are bent into C-shape, aline to form the key slot. An extending portion 19 of these fingers remains 80 horizontal, the fingers being bent again at 20, and suitable holes 21 are again provided to permit of a substantial union between the back and the shoe. The fingers thus are bent upwardly at 16, extend horizontally 85 from the line 22 to the line 23, extend vertically from the line 23 to the line 20, and then again extend horizontally. The openings 18 aline to form the key lug. A central strip 24 of the back remains intact for 90 strengthening purposes. Again it will be seen that the back remains in its original condition except that it is given the necessary curvature.

In Fig. 5, I show a modified form of the 95 invention in which the fingers 15^a and 15^a are drawn from the body portion 3 at right angles to the manner of drawing them in Fig. 4.

From what has been described it is 100 thought the nature of my invention will be readily clear to those skilled in the art.

Having however thus described several forms which my invention may take, what I claim as new and desire to secure by Letters 105 Patent is;

1. A back for a brake shoe provided with a key lug, said key lug consisting of two untwisted fingers drawn out of the body of the back without bending the remaining portions of the said back.
  2. A back for a brake shoe provided with a key lug, said key lug consisting of two cooperating, interlocking fingers formed out of the body of the back.
  - 10 3. A back for a brake shoe provided with a key lug, said key lug consisting of two oppositely extending untwisted fingers drawn out of the body of the back without bending the remaining portions of the said back.
  - 15 4. A back for a brake shoe provided with a key lug, said key lug consisting of two cooperating, interlocking oppositely extending fingers formed out of the body of the back.
  - 20 5. A back for a brake shoe provided with a key lug, said key lug consisting of two untwisted fingers drawn out of the body of the back, each forming a portion of said lug without bending the remaining portions of the said back.
  - 25 6. A back for a brake shoe provided with a key lug, said key lug consisting of two oppositely extending untwisted fingers formed out of the body of the back, each forming a portion of said lug.
  - 30 7. A back for a brake shoe provided with a key lug, said key lug consisting of two
8. A back for a brake shoe provided with a key lug, said key lug consisting of two fingers drawn out of the body of the back without twisting said fingers.
  9. A back for a brake shoe having a key lug formed of two oppositely extending untwisted fingers drawn out of the body of the back within its edges.
  10. A back for a brake shoe provided with a key lug consisting of two oppositely extending untwisted fingers drawn out of the body of the back, in one operation.
  11. A back for a brake shoe provided with two key lugs formed of two oppositely extending fingers drawn out of the back, each forming a portion of said key lug.
  12. A back for a brake shoe provided with a key lug consisting of two oppositely extending fingers drawn out of the body of the back, in one operation.
  13. A back for a brake shoe having fingers stamped to form a holding lug for said back.

In witness whereof, I hereunto subscribe my name this 16th day of February, A. D. 1916.

CHARLES W. ARMBRUST.
